UNITED STATES PATENT OFFICE.

ROBERT ELLIN, OF YONKERS, NEW YORK.

CRUSHING OR GRINDING MILL.

SPECIFICATION forming part of Letters Patent No. 624,774, dated May 9, 1899.

Application filed March 3, 1898. Serial No. 672,426. (No model.)

To all whom it may concern:

Be it known that I, ROBERT ELLIN, a citizen of the United States, residing at Yonkers, in the county of Westchester and State 5 of New York, have invented new and useful Improvements in Crushing or Grinding Mills, of which the following is a specification.

By means of this invention a mill is obtained which can be readily set for the required work 10 and effectively fed, as set forth in the following specification and claims and illustrated in the annexed drawings, in which—

Figure 1 is a sectional elevation of the mill. Fig. 2 is a section along *w w*, Fig. 1. Fig. 3 15 is a section along *x x*, Fig. 2. Fig. 4 is a section along *y y*, Fig. 2. Fig. 5 is a section along *z z*, Fig. 2.

These mills, as known, have revolving, crushing, or grinding wheels 1, generally 20 three or four in number, although this number can be varied. The wheels are ranged about or run over the bottom 2 of a pan or chamber and are shown with their shafts 3 having bearings or sleeves 4, jointed or hinged 25 at 5 to a central or upright shaft 6, suitably rotated by any suitable means—as, for example, by gears 7, 8, and 9, Fig. 1. The sleeves or bearings 4 are each shown with a lug or tapped eye 10 for the engagement of screw 11. 30 Between screw 11 and driving-shaft 6 is braced or compressed a spring 12, which tends to swing bearing 4, with wheel 1, downward or toward bottom 2. By setting or adjusting screw 11 the tension of the spring can be regulated.

The material to be treated or crushed is fed from the center to or under the wheels. The central feed is shown formed by a hopper 13, Fig. 1, from which passages 14 lead into hollow 40 shaft 6. Falling on the conical distributor 15, Figs. 1 and 3, the material passes through openings 16 and chutes or lateral branches 17, discharging at mouths 18 on the bottom 2 in front of the wheels 1. If seen fit, the material instead of being fed through hopper 13 45 can be fed into the shaft 6, as from its top at 19, Fig. 1.

To support or step the shaft 6 at its lower part is a bearing or shoulder 20, Figs. 1 and 50 3, which can be adjusted. The bearing 20 is shown forming part of a screw or thimble 21,

inserted into a suitable tap in the main frame or support of the mill, and by rotating the body 21 the shoulder or bearing 20 can be set higher or lower.

The shaft 6 is shown with a shoulder 22, between which and the bearing 20 is a spring or elastic or yielding ring 23, a metallic ring 24, and antifriction-balls 25. Below the shoulder 20 is a spring 26, Fig. 1, with metallic ring 60 27 and balls 28. The balls 28 run about on a shoulder 29, shown in form of a cap and adjustably secured by screw 30 to shaft 6. The springs 23 and 26 operate to hold the balls 25 and 28 to their seats under varying vertical 65 movements of the shaft owing to the grinding-wheels encountering pieces of material that are not readily crushed and also to permit of the vertical adjustment of the shaft. By setting or turning the bearing 20 higher 70 or lower the shaft, with the wheels 1, is set in proper position relative to bottom 2 or to the material under treatment. The shoulder 29 prevents shaft 6 lifting or rising out of place, and such shoulder can be adjusted as required for snugly confining the balls 28. Said 75 balls 28 and 25 ease the rotation of the shaft.

The bearing 20 can be rotated or set by gear 31, Fig. 1, suitably feathered on thimble 21 and actuated by miter-gear 32 and shaft 33, 80 suitably located to be in reach or accessible to the attendant. The gear 31 is suitably supported by ring or carrier 34, secured to the main frame or support 35 of the machine. By mounting gear 31 on antifriction-balls its 85 rotation is eased. The rotation of gear 31 and of screw 30 will effect adjustment, as seen.

The side of the pan is provided with or formed by a screen 36, as is customary in mills 90 of this kind. The feed 13 or 19, being central or within the arrangement of wheels 1, is in position to effectively supply material to each wheel through the mouth parts 18 of conduits 17. The gear 8 is shown drum-shaped or of 95 such size that the shaft 6, with its gear 7, can be adjusted or move without losing mesh. The central hopper revolving with or forming part of shaft 6, said hopper being provided with conduit or pipes, the proper proportion 100 of material to be crushed is conveyed and deposited simultaneously, constantly, and with

certainty upon the circular die or crushing path 2 immediately in front of each crushing wheel.

What I claim as new, and desire to secure by Letters Patent, is—

1. In a grinding-mill, the combination with a pan and grinding-wheels, of a centrally-arranged hollow shaft provided with a feed-hopper and having a plurality of perforations formed at a point beneath the hopper, a conical distributor arranged in said hollow shaft, the base of said conical distributor extending entirely to the inner wall of the hollow shaft at a point immediately below the perforations therein, and a plurality of feed-chutes leading from said perforations and terminating between the grinding-wheels, substantially as described.
2. In a grinding-mill, the combination with a pan and grinding-wheels, of a centrally-arranged hollow shaft provided with a feed-hopper surrounding the shaft and provided with a discharge end disposed centrally within the shaft, said shaft having a plurality of feed-openings establishing communication between the upper outer portion and the inner lower portion of the hopper, a conical distributor arranged in the hollow shaft beneath the hopper, and a plurality of feed-chutes leading from the hollow shaft at the base of the distributor downwardly between the grinding-wheels, substantially as described.

3. In a grinding-mill, the combination with a pan, of an upright shaft, radial sleeves hinged to the shaft, horizontal shafts journaled in said sleeves and carrying at their outer ends grinding-wheels arranged to travel in a circular path in said pan, springs arranged above the sleeves and bearing at one end against the upright shaft and at their opposite ends against a support on the upper side of the sleeves, and means for adjusting the tension of the springs, substantially as described.

4. In a grinding-mill, the combination with a pan, of an upright shaft, radial sleeves hinged to the shaft and each provided with a threaded eye, screws fitted in said eyes, coiled springs interposed between the ends of said screws and the upright shaft, horizontal shafts journaled in the sleeves, and grinding-wheels mounted on the outer ends of said shafts and arranged to travel in a circular path in the pan, said screws operating to adjust the tension of said springs and press the wheels into the pan with an adjustable pressure, substantially as described.

In testimony whereof I have hereunto set my hand in the presence of two subscribing witnesses.

ROBERT ELLIN.
